UNITED STATES PATENT OFFICE.

JOHN PLAYER, OF TOPEKA, KANSAS.

DESIGN FOR A CAR-BOLSTER.

SPECIFICATION forming part of Design No. 28,574, dated May 10, 1898.

Application filed March 17, 1898. Serial No. 674,265. Term of patent 14 years.

To all whom it may concern:

Be it known that I, JOHN PLAYER, a citizen of the United States, residing at Topeka, in the county of Shawnee and State of Kansas, have invented and produced a new and useful Design in Car-Bolsters, reference being had to the accompanying drawings, forming a part thereof.

In the accompanying drawings, Figure 1 is a plan view, partly in section, of a car-bolster constructed according to my design; Fig. 2, a side elevation of the same, partly in section; Fig. 3, a transverse sectional view taken on the line 3 of Fig. 2, and Fig. 4 an end view 5 looking at the bolster from the right-hand side of the drawings.

The leading feature of my design consists in a substantially circular or curved body portion cambered at top and bottom and narrowing from the central portion to the end thereof.

In the accompanying drawings, A is the body portion of the bolster, substantially curved or circular in end view, cambered at a and a' , and provided with substantially 25 rectangular projecting portions B B, also provided with a circular opening b in the bottom side and the openings b' on the side portion thereof, and C is a flat upper portion, the whole presenting to the eye a harmonious and ornate figure, as shown in the accompanying drawings.

I claim—

A design for a car-bolster substantially as herein shown and described.

JOHN PLAYER.
